TRANSFERRING OR DISPENSING SKIRTED PAPER DISKS OR CAPS AND THE LIKE

Application filed June 23, 1926. Serial No. 118,056.

This invention relates to dispensing flexible skirted caps or cups made of paper or other fibrous material, successively from a usually vertical column or stack of such articles in a magazine or holder, and delivery thereof one by one for use, or for depositing such articles on container heads in position thereon for hood capping and securing purposes; and the objects and nature of the invention will be readily understood by those skilled in the art in the light of the following descriptions of the accompanying drawings that illustrate what we now believe to be the preferred mechanical expression or embodiment from among other formations, constructions, arrangements and combinations within the spirit and scope of the invention.

An object of the invention is to improve the method of assembling and dispensing hood caps, and provide improved and efficient mechanism for transferring such skirted or cup-like articles from a stack or from a magazine to the point of use or delivery.

With the foregoing and other objects in view, the invention consists in certain method steps and in novel features in constructions, arrangements, and cooperation of parts, and in combinations, as more fully explained and specified hereinafter.

Referring to the accompanying drawings forming a part hereof:

Fig. 1 shows in sectional elevation mechanism embodying the invention, a bottle head being shown below the cap magazine, the cap transfer being shown in position where it has initiated its downward movement and consequently has just taken hold of the bottom cap of the stack preparatory to separating the same from the stack and removing the same from the magazine.

Fig. 2 shows the mechanism and certain parts in sectional elevation, in position with the cap applied to the bottle head, and the actuating arm completing its downward stroke to cause release of the grippers from the cap skirt.

Fig. 3 is a sectional elevation showing the opposite side of the mechanism from that illustrated by Fig. 1, with the parts in cap gripping position as in Fig. 1.

Fig. 4 is a top plan of the transfer mechanism with the parts in the positions shown by Fig. 1, the magazine not being shown.

Fig. 5 is a detail sectional view taken in the plane of the line 5—5, Fig. 3.

Fig. 6 is a detail sectional elevation showing the parts in position when the grippers are closing in to grip the cap and the downward movement is being initiated, just before the positions of Fig. 5 are reached.

Fig. 7 is a detail sectional elevation with the parts in the same positions as in Figs. 1, 3 and 5, the cap having been gripped and about to start on its downward movement preparatory to reversal.

Fig. 8 is a detail sectional elevation with the cap receiving head at its limit of upward movement and the gripping fingers moving in to grasp the cap.

Fig. 9 is a detail sectional elevation taken in a plane at right angles to the plane of the section Fig. 8 and showing the parts in the same positions as in Fig. 8.

Fig. 10 is a detail sectional elevation showing the initial position of the parts when the cap is applied to the bottle mouth, as in Fig. 2, the transfer arm being shown as completing its downward movement to cause withdrawal of the gripping fingers from the cap.

Fig. 11 is a detail sectional elevation showing the position of the parts when the gripping finger releasing movement is continued from the positions of Fig. 10, to move the gripping fingers from the cap, and to permit movement of the automatic latch to locking position as in Fig. 12.

Fig. 12 is a detail section showing the position of the parts approximately as in Fig. 11 with the latch in locking position.

Fig. 13 is a detail elevation showing the initial position of the parts just before the latch automatically drops from locking position, preparatory to the completion of the cap securing or grasping upward movement.

Fig. 14 is a detail top plan of the cap receiving head or plunger.

Fig. 15 is a section of said head.

Fig. 16 is a detail elevation of the rotary or reversing carrier of the transfer.

Fig. 17 is a top plan of said carrier.
Fig. 18 is a plan of the latch collar.

Fig. 19 is an elevation of said collar.

In the drawings, a container *a*, such as a glass or other milk bottle, to be hood capped, is shown vertically spaced from and located below a vertically elongated tube or magazine 1, for a supply of flexible paper or other fibrous material hood caps or paper cups or the like, *b*. In the particular example illustrated, the vertical longitudinal axes of the container *a*, to be hood capped and the magazine 1, or the stack or caps *b*, therein, are aligned.

15 A vertical stack or pile of caps *b*, is shown in the magazine 1, and the caps *b*, of the stack or pile are arranged in reversed position, i. e. all in the same position upside down or with their skirts extending upwardly, and 20 the caps are all more or less closely nested together. The stack of caps *b*, is loosely arranged in the magazine feed tube 1, to freely drop or feed down therein by gravity or otherwise, and so as to be freely movable 25 vertically therein to and above the means for supporting or upholding the stack against dropping from said tube. The lower end of the magazine or tube is open for successive removal of the bottom caps of the stack, 30 when such bottom cap is distorted and pulled down with sufficient force to separate the cap from those above and pull the cap past the cap stack support.

35 In the particular example shown, the cap stack is upheld in the magazine tube by several spaced radial lugs or fingers 1*a*, rigid with and projecting inwardly from a fixed internal annular ledge or ring 1*b*, within the discharge mouth or lower end of the magazine tube. The arrangement, in this 40 example, is such that the bottom cap of the stack rests on the inner ends of the stack upholding fingers 1*a*, which engage the cap skirt at spaced points in a circle around the 45 same, say about midway the vertical length of said skirt, so that the closed end of the cap depends from and a distance below the lower end of the magazine tube, in other words, the bottom cap of the stack is accessible below the magazine tube. The lower 50 end of the magazine is preferably formed or provided with an exterior-normally-fixed or rigid abutment wall or ring 1*c*, surrounding the open or discharge end of the magazine.

55 Any suitable stand or support, such as *c*, Fig. 3, is provided for and on which rests the container *a*, to be hood capped, and this stand is preferably formed or arranged to approximately center the container in hood capping position under and with respect to the column of caps in the magazine.

60 Any suitable means (not shown) is provided to uphold and support the cap magazine a distance above and overhanging the container that is located in hood capping po-

sition, and in a normally fixed or stationary position with respect to said container and its stand and also with respect to the cap transfer mechanism hereinafter described in detail.

70 The problem is to take the bottom cap from the magazine and then reverse the cap, and deliver the same right side up, or, in the particular relation of the example shown, to then apply the cap to hood capping position 75 on and covering the head of the container located in hood cap receiving position.

80 The drawings disclose one example of mechanism, from among others, that solves the problem and performs the desired functions, and in this example a vertically movable support, such as a slide or bracket is reciprocated vertically between the lower end of the magazine and the head of the container that is in cap receiving position, and this slide or support carries cap holding and grasping means, whereby the cap separation, 85 reversal and applying is accomplished.

89 The support, that we happen to show as an example, embodies a horizontally disposed bracket or arm 2, rigid with or carried by vertical slide or sleeve 2*a*, slidably confined to and reciprocable longitudinally of the fixed or stationary guide rod or post 3, suitably secured to the machine base or framework (not shown) and arranged behind or spaced laterally a distance from the magazine 1, and the container stand or other support.

95 The bracket arm 2, projects laterally from its carrying slide 2*a*, to a position interposed 100 between the magazine and the head of the container that is in cap receiving position, and any suitable actuating means is provided to reciprocate said arm vertically back and forth between the lower end of the magazine and 105 said container head.

110 For instance, the arm can be actuated and its vertical position controlled by a pitman or link 4, operated by any suitable part (not shown) of the machine, and at its upper end having compensating and yielding operative connection with the arm 2, through the medium of slide bolt 5, and compression spring 6. The vertical bolt 5, extends and has limited 115 relative vertical sliding movement through a vertical bore or hole through the arm; and the compensating spring 6, surrounds the bolt 5, above and at its lower end abuts the arm while the upper end of the spring abuts an adjustable nut or other abutment 5*a*, on the bolt 5. 120 The bolt at a point below the arm 2, is provided with a stop 5*c*, to strike and lift the arm with the bolt. The compensating spring is arranged to provide a yielding downward 125 pressure on the bottle heads and to compensate for certain differences in bottle lengths.

130 In the particular example illustrated where the vertically movable support of the cap transfer embodies an arm, such as 2, a reversing cap holder and grasping assembly or

mechanism is carried by and arranged at the free end of the arm directly between the cap magazine and the bottle or container head.

In this particular embodiment, the free end 5 of the arm 2, fixedly carries or is formed with a transversely-arranged elongated horizontal hub 2b, the axis of the bore of which is at right angles to the longitudinal axis of the arm, and forms an elongated bearing for and 10 receives a horizontal rock shaft 7, that extends and projects beyond said hub and is arranged transversely of the arm. At one projecting end, this rock shaft or spindle carries a pinion 7a, fixed thereto, and at its other end beyond 15 the hub 2b, said shaft carries an enlarged head 7b, rigid therewith and carrying the cap holder and cooperating parts.

The cap holder embodies a plunger comprising a cap-receiving approximately flat 20 disk, face plate or head 8, and a shank 8a, normally rigid with said face plate and centrally and perpendicularly arranged with respect thereto and depending therefrom when the face plate is arranged above head 7b.

25 The plunger consisting of face plate 8 and shank 8a, is carried by the head 7b, of rock shaft 7, with the face plate arranged beyond an end of the head, and with the shank 8a, extending and slidable through said head 30 diametrically with respect to the axis 7. The head 7b, is formed with a bore extending completely therethrough and the shank 8a, is slidably confined in said bore to permit limited reciprocation thereof relative to the 35 head. The reciprocation or relative independent movement of the face plate 8 of the plunger, is radial with respect to the axis 7.

The plunger movement of the face plate 8, toward the adjacent end of the head 7b, is 40 limited by engagement of said plate or parts carried thereby with the head, while outward straight-line movement of the face plate away from the head, is limited by engagement of collar 8b, fixed on the opposite projecting 45 end of the shank 8a, with the adjacent end of head 7b.

Suitable spring means is provided constantly tending to yieldingly hold the plunger with its face plate 8 at the limit of outward 50 movement away from the adjacent end of head 7b, and with the collar 8b, engaging the other end of said head (Fig. 5). For instance, an elongated coiled expansion spring 11, can be employed for this purpose, extending 55 across the collar 8b, and at its two ends operatively coupled to suitable means in such manner that the constant tendency of the spring to contract acts on the plunger to force the same outwardly. In the form shown, the 60 flexible distended spring is bent to U-shape with its central portion traversing the outer end of the collar 8b, which is formed with a transverse groove in which the spring is seated. The two legs of the U-spring extend forwardly beyond opposite edges of the head 7b,

and at their free ends are coupled to levers 12, pivoted to the face plate portion of the plunger and bearing or fulcruming against the adjacent end of the head 7b, in such manner that the spring is always distended under tension and acts on the plunger to project the same and its face plate outwardly as hereinbefore described.

70 The collar 8b, carries a pivoted vertically swingable detent or latch 14 provided with a vertically swingable weighted arm 14a. This latch is designed to assume locking position to hold the plunger at its approximate limit of inward movement or in withdrawn position (see Figs. 12 and 13) against the tension of spring 11, for a certain purpose and under certain conditions, and to automatically swing to and from such locking position under other conditions and positions. The latch 14 is in locked or locking position when 80 swung in between the collar 8b, and the adjacent end of the head 7b, with the nose of the latch abutting the adjacent end face of the head 7b.

85 The face plate 8, of the plunger is provided with a pair of radially-projecting diametrically opposite rigid arms, at their free ends having parallel rigid fingers 8c, projecting forwardly in advance of and at right angles to the general plane of the face plate 8, and these arms are arranged and designed to abut the normally fixed end surface 1c, of the cap magazine and limit the forward movement of the face plate toward the lower end of the magazine, for a definite purpose. The radial arms of the face plate 8 are longitudinally slotted and each formed with a pair of inwardly or rearwardly projecting ears 8d, between which the levers 12, are arranged and swingable on transverse pivots 12a, carried by said ears 8d. The two levers 12, converge from their supporting pivots and are arranged behind the face plate 8, with their inner or adjacent ends 12b curved or rounded and bearing against the flat adjacent end surface 7d, of head 7b, said adjacent end of said head being transversely grooved to receive and guide the inner ends of levers 12, and to provide the elongated abutting surface 7d on which the inner ends 12b, of the levers 12 can rock and slide. The front ends of retractile spring 11, are secured to the levers 12, respectively, at points between the pivoted points 12a, and the inner ends 12b, thereof, in such manner that the outward pressure of the spring against the collar 8b, of the plunger constantly tends to force the plunger outwardly with its face plate 8 at its limit of outward movement (Fig. 10) which causes 100 the levers 12, to assume inclined positions appearing in Fig. 10. The levers 12 are employed to provide and control cap grasping or picker fingers operating in front of the plunger head or face plate 8. In the example 105 illustrated, the levers 12 are in the form of 110

115

120

125

130

angle levers or are formed with free ends 12d extending forwardly and working through the slots in the radially projecting arms of the plunger face plate or head, and at their front free extremities provided with laterally projecting cap grasping sharp pin or needle-like points 12c, to puncture or at least to prick and grasp the paper or like material of the cap.

Any suitable means can be provided to reverse the position of the head 7b and its spindle 7, and consequently the cap carrying plunger (the plunger head 8 and its shank and the parts carried thereby) as these parts move from bottle capping position to cap supply and from cap supply to cap delivery or bottle capping position.

As an example for this purpose, we happen to show the toothed pinion 7a, meshing with and actuated and controlled by a longitudinally slideable rack 15, having roller 15a, at its inner end, constantly held against relatively fixed vertically-elongated cam track 16, by retractive spring 17, so that 25 the rack is longitudinally impelled in one direction by the spring and in the opposite by the high portions or elevations of the cam track, to thereby rotate the pinion 7a, in opposite directions and to the angular 30 distances necessary to reverse the cap holder and carrier at the predetermined up and down portions of the travel of the carrier 2.

The track 16 is vertically elongated and in the example shown is arranged longitudinally of and suitably secured to the post or guide rod 3.

The sliding rack 15, is arranged longitudinally of and is carried by the arm or carrier 2, and is held to straight line reciprocation through the medium of certain guideways carried by said arm 2.

The cap carrier or transfer reversing mechanism (that embodies said cam track, the rack and pinion) is so constructed and 45 arranged, as to present the plunger head 8, in horizontal position above arm 2, to the cap supply (the magazine 1) as the cap transfer approaches operative cap removing position or relation to said magazine and 50 to maintain said position until the cap carrier on its downward movement has withdrawn a distance from said magazine. When the carrier 2, on its downward stroke has carried the cap holder down clear of 55 the magazine, continued downward movement of carrier 2, causes the cam track, rack and pinion to initiate reversing rotation of the spindle 8a, head 8, and parts carried thereby which rotary movement is 60 continued through 180° until the plunger head or plate 8 again reaches horizontal position but below carrier arm 2, and this occurs before said head 8, reaches the head of the container on which the cap is to be 65 deposited.

The plunger 8, is in a horizontal position during the latter portion of the down stroke of the carrier 2, and also during the latter portion of the upward stroke of said carrier, and the plunger head is in effect locked or held in horizontal positions during said portions of the up and down strokes of the carrier 2, by the straight lengths of track 16 (see Fig. 2) through the medium of the 70 rack, pinion, and spring 17.

The plunger head 8 is reversed from its horizontal position above to its horizontal position below the carrier, about midway the length of the carrier down stroke, and about midway the length of the up stroke of the carrier, the plunger head is again reversed to assume its horizontal position above the carrier, all by reason of the inclined intermediate portion of the cam track 16, Fig. 2.

On the latter portion of the up stroke of the carrier, the plunger head 8 is in upper horizontal position to receive a cap, and the plunger is locked down with respect to head 7b, by the latch 14 in locking position (see Fig. 9) for the purpose of holding the cap pricking or gripping fingers 12d swung downwardly and outwardly to withdrawn positions with their prickers 12c, withdrawn from operative or cap engaging position (see Fig. 8). The cap carrying and holding parts are in these positions (Figs. 8, 9 and 13) when the fingers 8c, of the plunger move up into engagement with the relatively fixed end wall of 1c, of the cap magazine and stop further upward movement of the plunger. When the plunger thus reaches its limit of upward movement, the flat top face of the plunger head 8, is centrally seated against the flat center of the downwardly protruding bottom cap of the stack of caps in the magazine tube, and in fact said stack of caps is usually lifted by and upheld by said plunger head with the bottom cap centrally seated thereon midway between the two withdrawn grasping fingers 12d, the prickers 12c, of which are located approximately beside the skirt of the cap (Fig. 8).

When the plunger reaches its limit of upward movement by reason of the fingers 8c, abutting the magazine end wall, the carrier 2, has not fully completed its upward stroke, but continues its relative or independent upward movement for the slight distance necessary to relieve the pressure of the spring 11, holding the latch 14 against the adjacent end wall of head 7b (Figs. 9 and 13) and free said latch so that under the action of its weighted arm 14a, said latch will swing outwardly to unlocking or released position. The parts otherwise will then be in positions as in Figs. 8 and 9, with the exception that the carrier 2 will be at its limit of upward movement with spring 11 fully distended, the top 115 of the head 7b, will be approximately against 120 125 130

the under side of plunger head 8, and the pricker fingers will be withdrawn to a slightly greater extent.

The carrier 2, now starts on its downward movement relative to or independent of the plunger which is then held at its limit of upward movement with its fingers 8c, against the tube magazine end, by the tension of spring 11 bearing upwardly against the plunger shank through the medium of collar 8b. The carrier 2 moves down on its independent movement until the lower end of head 7b, engages the plunger collar 8b (Fig. 5). This independent downward movement of the carrier 2 causes inward and upward swing of the gripping fingers 12d, to project to the prickers thereof into gripping engagement with or projection thereof into the skirt of the cap seated on the plunger head for the purpose of radially distorting the flexible cap skirt and grasping and holding the cap to and against the plunger head 8, on which the cap is seated, (see Figs. 1, 3, 5 and 7). The relative movement between the plunger and carrier 2, is provided to control the positions of the gripping fingers and to move said fingers to and from withdrawn or inoperative position and gripping or operative position under the action of the spring 11. The spring 11 not only holds the inner ends of the finger controlling lever arms 12 against the abutment floor 7d, of the head 7b and hence yieldingly impels the fingers on their gripping strokes, but also constantly exerts plunger projecting force or tension against the plunger through the engagement of the central portion of the spring against the plunger collar 8b, while the free ends of the springs bear in the opposite direction against the end 7d of head 7b, through the lever arms 12. The operative ends of the gripping fingers are swung toward or from each other by the relative movements between the plunger to which the levers 12-12d are fulcrumed, and the head 7b, against which the lever end 12 are held by the spring 11.

The carrier continues on its downward stroke after the lower end of the head 7b strikes collar 8b, (Fig. 5) and thus carries down the plunger and pulls the cap b, seated on and gripped to the plunger head 8, from the magazine and separates the same from the caps remaining in the stack. The two gripping fingers closing in on the cap skirts from diametrically opposite points tend to radially and inwardly compress and distort the cap skirt and thus aid in separating the same from the contacting cap above, and on the downward movement of the plunger with the carrier, the distortion of the flaring cap skirt, aids the gripping fingers in stripping the cap past the cap stack upholding lugs 1a, and from the discharge mouth of the magazine tube.

55 The carrier and the plunger then move

down together below the magazine, with the flat top seated against plunger head 8, and the flaring cap skirt extending upwardly therefrom and grasped by the gripping fingers. As the downward movement continues, the roller of the rack 15, travels down the intermediate inclined portion of track 16, and through rack 15, and pinion 7a, the spindle 7 and head 7b are rotated to reverse the plunger to a depending position wherein the horizontal plunger head 8, is centered above and axially over the container head to be capped with the cap in proper upright position held to the under face of said head and the flaring cap skirt depending. The carrier 2 and plunger then move down together until the cap is properly positioned on the container head, as in Figs. 2 and 10. The plunger thus reaches its limit of downward movement and presses the flat top of the cap tightly down on the top edge of the bottle mouth, while the carrier 2, continues down independently of the plunger and against the tension of the spring 11, to swing the cap gripping fingers outwardly to withdrawn or inoperative position and clear of the cap skirt, whereby the cap is properly seated on the container head and released from the securing or cap grasping fingers (see Fig. 11). The carrier 2, continues on its independent downward movement for a slight distance until the latch 14, (in this example under the action of gravity) automatically swings in to locking position between the collar 8b, and the adjacent end of head 7b, as shown by Fig. 12. The carrier 2, has then approximately reached its limit of downward movement, and thereupon the carrier and plunger start on their upward movement, the plunger being now locked in withdrawn position against the tension of spring 11, by latch 14. On moving up the plunger leaves the cap properly seated on and covering the container head in position and readiness for securing thereon by contraction of the cap skirt under the exterior enlargement or rim of the container head, and securing in any suitable manner or by any desirable method or means.

50 The carrier and the empty plunger continue on the upward stroke, and intermediate the length thereof, the reversal takes place to bring the plunger to position above the carrier to receive and take a cap from the cap supply as hereinbefore described.

55 The up and down reciprocations are preferably timed with the bottle or container feed to apply hood caps to the containers as rapidly as capped containers are removed from and containers to be capped are brought to the cap receiving position alined with the cap supply and the vertical path of reciprocation of the cap transfer.

60 It will be noted that the cap transfer will not drop or deliver the cap carried thereby

70

130

if it so happens that no container is at the cap receiving position when the cap carrying plunger reaches cap delivery position, but in such event the cap is retained by the 5 plunger on the up and down strokes, until a bottle is present against which the plunger head can abut to cause the independent movement of the carrier necessary to cause withdrawal of the cap grasping fingers from the 10 cap.

The cap transfer travels in a vertical line, in this example, back and forth between the cap supply and the cap delivery point and automatically secures a cap from the supply 15 and reverses the cap and automatically deposits the cap in proper position on the bottle head, if a bottle head is present to cause actuation of the cap release means, otherwise the cap is retained by the transfer until 20 a bottle head or some other abutment at the cap delivery point causes the relative plunger and carrier movement to release the cap from the gripper fingers.

At the cap supply, the bottom wall of the 25 cap magazine constitutes an abutment to stop the plunger and permit the relative movement of the carrier that brings about cap grasping movement of the cap gripper fingers.

30 At the cap delivery point, the bottle head constitutes the abutment to stop the plunger and permit the relative movement of the carrier that brings about cap releasing movement of the gripper fingers, so that in effect, 35 the cap transfer also constitutes a bottle finder, or a cap delivery point finder, inasmuch as an abutment or the like is needed to locate the point at which the cap is delivered and deposited.

40 Of course, where the cap transfer delivers cup like paper articles for other purposes than bottle hood capping, a bottle head will not be used for the delivery point determining abutment, but some other means or equivalent 45 can be utilized for this purpose.

It is believed to be obvious that various changes, modifications, and variations might be resorted to, that parts might be omitted and features might be added, all without departing from the spirit and scope of the invention, and hence we do not wish to limit ourselves to the approximate disclosure hereof.

50 What we claim is:—

55 1. A cap transfer for removing caps successively from a cap supply and depositing the same in hood capping position on container heads, comprising a plunger having a plunger head and grippers for grasping a cap 60 and holding the same to said head, and a movable carrier for conveying said plunger back and forth between a cap supply and the point of cap delivery, said plunger having a range of independent movement with respect to said carrier, said grippers being

65 moved to gripping and to cap releasing position by said relative movement, means being provided to control and time said relative gripper operating movements.

2. In combination, a magazine having 70 means at its bottom discharge for upholding a stack of flexible skirted paper caps or the like, means for supporting a container the head of which is to be hood capped, a cap carrier, and means for moving the same back 75 and forth between said bottom discharge and the container head to be capped, said cap carrier embodying cap grasping and releasing means to grasp the bottom cap of the stack by its skirt to distort the same and pull the cap down from the stack and magazine and to release the cap when deposited in hood capping position on the container head.

3. In combination, a magazine having 80 means at its bottom discharge for upholding a stack of flexible skirted paper caps or the like, means for supporting a container the head of which is to be hood capped, a cap carrier, and means for moving the carrier back 85 and forth between said bottom discharge and the container head to be capped, said cap carrier embodying cap grasping and releasing means to grasp the bottom cap of the stack by its skirt to distort the same and pull the cap 90 down from the stack and magazine and to release the cap when deposited in hood capping position on the container head, said cap carrier also embodying means whereby said 95 grasping and releasing means is relatively movable and spring actuated to and spring held in cap gripping position, and is positively actuated to cap grasping position by engagement with the magazine end and to cap releasing position by engagement with the container head.

4. In combination, a magazine having 100 means at its bottom discharge for upholding a stack of flexible skirted paper caps or the like, means for supporting a container the head of which is to be hood capped, a cap carrier, and means for moving the carrier back 105 and forth between said bottom discharge and the container head to be capped, said cap carrier embodying cap grasping and releasing means to grasp the bottom cap of the stack by its skirt to pull the cap down from the stack and magazine and to release the cap when deposited in hood capping position on the container head, said cap carrier also embodying means whereby said 110 grasping and releasing means is actuated to cap gripping position by engagement with the magazine end and to cap releasing position by engagement with the container head.

5. In combination, a cap supply, an adjacent abutment, a support for the container the head of which is to be hood capped, a cap carrier, and means for conveying said cap carrier back and forth between said supply 115 and the head of the container, said cap car-

rier embodying a head having limited relative movement with respect to said means, cap gripping fingers swung to and from cap gripping positions by said relative movement between the head and said means, spring means constantly tending to impel said head to its limit of relative movement in one direction, and a latch for locking said head approximately at its limit of relative movement against the tension of said spring means and for releasing said head for relative movement, said abutment and said container head serving to stop said head to permit said relative movement to cause cap grasping and cap releasing movements of said fingers.

6. In combination, a vertical cap magazine for a stack of flexible skirted cup like paper articles having means at its open lower end to uphold the stack, and a cap transfer for successively grasping the bottom caps of the stack and stripping them downwardly from the stack and past said means and conveying the same to a point of delivery, said transfer embodying a carrier, a cap receiving head, cap skirt distorting fingers arranged beside and extending beyond the cap receiving face of said head to grasp a cap by its skirt and distort the skirt and hold the cap to said face of the head, said fingers being movable to grasp and to release the cap, and means timing and causing cap grasping and cap releasing movements of said fingers.

7. In combination, in a transfer for cup-like skirted paper articles, such as hood caps, a carrier having a path of movement back and forth between a cap supply and a point of cap delivery, and a cap holding and releasing assembly transported by said carrier and embodying a head adapted to have the cap top seated thereagainst, swingable fingers extending at opposite sides of and beyond said head and having prickers arranged to move inwardly against a cap skirt to grasp the skirt and hold the cap against the head, means being provided whereby the fingers are moved to grasp a cap and to release a cap, and means timing and controlling the cap grasping and releasing movements of the fingers.

8. A cap transfer comprising a movable carrier, a cap receiving head carried thereby and having a limited range of relative movement with respect thereto, a spring constantly tending to project said head to its outward limit, an automatic gravity latch to hold said head approximately at its opposite limit against the tension of said spring, and cap gripping fingers fulcrumed to said head and held bearing against said carrier by said spring and swung to and from cap grasping and cap releasing positions by said relative movements between the head and carrier.

9. In combination, means for holding a stack of paper material hood caps and for

feeding the same to a discharge mouth for successive delivery of the caps therefrom, and hood cap transferring and applying mechanism for removing the caps one by one from the stack and placing the same on the heads of containers for subsequent clamping thereon, said mechanism including spring means whereby the caps are pressed down against the container heads under yielding pressure.

10. Means for holding a stack of paper material hood caps in reversed or upside down position and for feeding the same to a discharge mouth for successive delivery of the caps therefrom, in combination with a cap transferring and applying mechanism movable back and forth between said discharge mouth and a container head for positively engaging and holding the end cap of the stack and stripping the same therefrom and from said mouth and positively applying the same to and pressing the same on a container head, said mechanism embodying a relatively movable hood cap holder, means whereby said holder is movable to reverse the cap held thereby on the movement from said mouth to the container head to place the cap on the head right side up, and whereby the holder on the return movement is restored to its original position to secure the upside down cap from the stack preparatory to reversing the same, and means for causing the cap to be held to and released from the holder, controlled by the relative movement of said holder.

11. A vertical hood cap disk magazine having an open discharge end and internal means to loosely uphold a column of hood cap disks, in combination with a hood cap disk transferring, reversing and applying mechanism movable back and forth in a vertical path of movement between said end of the magazine and the head of a container located a distance from and aligned with said magazine end and embodying means to take hold of and pull the bottom disk in the magazine past said means and from the magazine end, reverse the disk and apply the same right side up directly to the container head.

12. Mechanism for successively moving caps in upside down position from a cap supply and delivering the same right side up at the points of delivery, comprising a reciprocating carrier, a cap holding and delivering assembly conveyed by said carrier back and forth between the cap supply and the points of cap delivery and relatively reversible with respect to the carrier including a spring held relatively movable member for pressure against the cap supply to actuate the cap grasping action, and means for automatically reversing the position of said assembly on each delivery stroke and on each return stroke between the supply and delivery points.

13. In combination, a support for a con-

- tainer the head of which is to be hood capped, means to provide a supply of hood cap disks and an adjacent abutment, a carrier movable on disk applying and transporting strokes from said disk supply towards said container head and on its return strokes from said container head toward said disk supply and a disk securing, applying and releasing assembly conveyed by said carrier and movable
- 10 with respect thereto to reversed positions on the carrier stroke toward the container head and on the return stroke from the container head, means being provided for automatically effecting the movement of the assembly to
- 15 reversed positions, said assembly being actuated to grasp a cap by pressure against said abutment and to release a cap by pressure against the container head.
14. Mechanism for transferring skirted
- 20 cap or cup-like articles from a supply to the point of delivery comprising a carrier reciprocatory back and forth from the supply to the point of delivery, cap securing and delivering means conveyed by said carrier and
- 25 relatively movable with respect thereto, and means for automatically moving said cap securing and delivering means to reverse the position thereof on each stroke of the carrier to the point of delivery and to move said set-
- 30 curing and delivering means to its former position on each return stroke of the carrier, said means being arranged to abut the cap supply and cause the cap securing action and to abut the container head at the point of de-
- 35 livery to cause cap release.
15. In combination, means for successively delivering skirted hood cap disks at a discharge mouth; and cap transfer mechanism for forcibly stripping each disk from said
- 40 mouth and transferring the same to and forcing the same right side up under yielding pressure down on container heads for securing thereon, said mechanism embodying spring means to provide for said yielding applying pressure, a relatively-yielding disk carrying member to press against the disk at said mouth and to press the disk down on the container head and against which member the center of the disk is held and maintained
- 45 while the disk is being forcibly stripped from said mouth and during transfer, and means controlled by said relative yielding of said member for holding the disk to and releasing the same from said member.
- 50 16. In combination; a cap supply; a support for a container to be hood capped; and cap transfer and applying mechanism movable back and forth between said supply to secure a cap therefrom and the container head
- 55 to deposit the cap thereon, said mechanism including a cap holder, and means whereby the cap at the supply is held to said holder, for detachment from the supply and transportation to the container head, and whereby
- 60 said cap is released from said holder by the continued downward pressure of the holder on the container head.
17. In combination; a hood cap supply; an abutment; a support for a container to be capped; and cap transferring and applying mechanism movable back and forth between said supply and the container head to secure a cap at said supply and transport the same to and deliver the same on the container head, and means causing the cap to be held by said mechanism for removal from the supply and transportation, and to be released from said mechanism when the cap is seated on the container head, said last mentioned means including a relatively yielding member to be actuated by engagement with said abutment to cause the cap to be held to said mechanism and to be actuated by downward pressure on the container to cause release of the cap.
18. In combination; a cap supply for holding a cap in reversed position; and cap transfer mechanism for removing the cap from said supply and turning the cap over while transferring the same to and pressing the same in upright position down on a container head, said mechanism embodying means whereby the cap is held to said mechanism and thus removed from the supply, and transferred and applied to the bottle head, and a relatively-yielding member to cause release of the cap on the container head by relative movement between said member and said mechanism while exerting downward pressure on said container head.
19. In combination; a hood cap supply for holding a hood cap in reversed position; and hood cap transfer mechanism for removing the cap from said supply and turning the cap over while transferring the same to a bottle head and for depositing the cap in upright position on the bottle head, said mechanism embodying means whereby the cap is held to the mechanism and thus stripped and pulled from the supply and transferred and applied to and released on the bottle head, and a relatively yielding member to cause release of the cap on the bottle head by relative movement between said member and said mechanism.
20. A magazine having an open discharge mouth, said magazine adapted to receive a stack of nested flexible paper hood caps in reversed position closed end foremost and to feed the same toward said mouth as caps are successively removed therefrom, means being provided to support the caps in said magazine with the end cap accessible at said mouth for stripping from the stack and said means and withdrawal from said mouth; in combination with hood cap transferring, reversing and discharging mechanism for successively pulling and stripping the end caps of said stack therefrom and from said means and removing the caps from said mouth and turning the caps over and discharging the same

right-side up in bottle hood capping position.

21. A magazine having a discharge mouth, said magazine adapted to receive a stack of nested flexible paper skirted hood caps and to feed the same toward said mouth as caps are successively removed therefrom, and cap skirt engaging means projecting into said mouth to support the caps in the magazine with the end cap accessible at said mouth for grasping and stripping from the stack and past said means and for withdrawal from the mouth; in combination with a support for holding a bottle with its head opposite and approximately longitudinally alined with said mouth; and mechanism movable vertically back and forth between said mouth and the hood cap releasing position on the bottle head, for successively pulling the flexible end caps from the stack and past said means and downwardly from said mouth and for releasing the caps in hood capping position on the bottle mouths, for subsequent contraction and securing of the flexible cap skirts under the bottle rims.

22. A magazine having a discharge mouth, said magazine adapted to receive a stack of nested flexible paper skirted hood caps and to feed the same toward said mouth as caps are successively removed therefrom, and cap skirt engaging means projecting into said mouth to support the caps in the magazine with the end cap accessible at said mouth for grasping and stripping from the stack and past said means and for withdrawal from the mouth; in combination with a support for holding a bottle with its head opposite and approximately longitudinally alined with said mouth; and mechanism movable vertically back and forth between said mouth and the hood cap releasing position on the bottle head, for successively pulling the flexible end caps from the stack and past said means and downwardly from said mouth and for releasing the caps in hood capping position on the bottle mouths, for subsequent contraction and securing of the flexible cap skirts under the bottle rims, said mechanism including a relatively movable member for cooperating with an abutment.

23. A vertical magazine having a discharge mouth, said magazine adapted to receive a stack of nested annular skirted flexible paper hood caps in reversed position and to feed said caps toward said mouth as the end caps are removed therefrom, means being provided to uphold the stack in said magazine; in combination with a flexible hood cap transferring, reversing and applying mechanism movable back and forth between said magazine mouth and a bottle head located a distance from and approximately alined with said mouth, and including means to take hold of and pull and strip the end cap from the stack and past said means and from the mouth, reverse the cap, and apply the

same right-side up to and release the same on a bottle head.

24. Apparatus for exteriorly covering bottle heads with flexible paper hood caps having depending flaring annular skirts, said apparatus embodying a feed and holding magazine for and adapted to uphold a stack of said skirted hood caps in reversed position with their skirts extending upwardly, said magazine adapted for the free downward feeding of the stack of reversed caps to a discharge mouth; said apparatus providing a station to which successive bottle heads and successive hood caps right-side up with their skirts depending are brought together; and mechanism including cap reversing means for successively withdrawing reversed hood caps through said discharge mouth and conveying said caps to said station while turning said caps over and delivering the same right-side up at said station.

25. In the method of exteriorly covering the heads of bottles with flexible paper hood caps having depending skirts, those steps which include arranging a stack of said hood caps in reversed position with their skirts extending upwardly to facilitate the free downward feeding of the caps without spreading the skirts thereof; successively stripping and removing the reversed bottom caps from said stack and conveying the same to a bottle capping position while turning the cap over and delivering each cap right-side up with its skirt depending, and bringing together the caps while right-side up and the bottle heads to exteriorly cover said heads.

26. Means for dispensing sheet paper material annularly skirted hood caps from a cap discharge mouth to the point where the cap is released while positioned on a container head, comprising a movable carrier, relatively movable cap grasping devices supported by said carrier and having prickers to grasp the cap skirts, operating means for actuating said carrier, and means to move said devices to grasp and release a cap.

27. In apparatus for dispensing flexible skirted hood caps for application to bottle heads to be hood capped thereby, means for supporting flexible skirted hood caps at a discharge and for successively supplying such caps to said discharge; and mechanism having strokes toward and from said discharge and provided with and carrying relatively movable means for grasping the caps successively by their flexible skirts and pulling the caps from said discharge and releasing the caps on bottle heads.

28. In apparatus for dispensing flexible skirted hood caps for application to bottle heads to be hood capped thereby, means for supporting flexible skirted hood caps at a discharge and for successively supplying such

caps to said discharge; and mechanism having strokes toward and from said discharge and provided with and carrying relatively movable pricker fingers for grasping the caps 5 successively by their flexible skirts and pulling the caps from said discharge and releasing the caps on bottle heads.

29. In machinery for hood capping bottles; in combination; a magazine adapted to carry 10 a stack of flexible sheet hood caps having their flaring annular flexible skirts all extending in the same direction and their closed tops or centers alined, and to feed said stack forward to a discharge; and a cap transfer 15 movable back and forth between said discharge and a cap delivery point for removing successive caps from said discharge and delivering them successively at said point, said transfer embodying cap-fitting means 20 to engage said top or center of each cap, and means whereby the top or center of each cap is thus held to said cap-fitting means and the cap is thereby transported to and released at said delivery point.

25 Signed at Fulton, Oswego County, New York, this 16th day of June, 1926.

WILBUR L. WRIGHT.
LEE D. PIERCE.
